WIRE STRETCHER

Jean Marie Thevenin, 08-Thilay, Ardennes, France

Filed Feb. 23, 1971, Ser. No. 118,203

Term of patent 14 years

Int. Cl. D8—05

U.S. Cl. D8—44

FIG. 1 is an elevational view in one position of the novel wire stretcher;

FIG. 2 is a plan view of the wire stretcher shown in FIG. 1 when the wire stretcher has been rotated from its FIG. 1 position 180° about a vertical axis and 90° about a horizontal axis; and

FIG. 3 is an enlarged left-hand view of the wire stretcher as viewed in the direction of the arrow in FIG. 1.

I claim:

The ornamental design for a wire stretcher, as shown.
